CLAIM

The ornamental design for a bag dispenser, as shown and described.

DESCRIPTION

FIG. 1 is a perspective view of a bag dispenser, showing our new design.

FIG. 2 is a right side view of the bag dispenser of FIG. 1.

FIG. 3 is a left side view of the bag dispenser of FIG. 1.

FIG. 4 is a front view of the bag dispenser of FIG. 1.

FIG. 5 is a rear view of the bag dispenser of FIG. 1.

FIG. 6 is a top view of the bag dispenser of FIG. 1; and,

FIG. 7 is a bottom view of the bag dispenser of FIG. 1.

The evenly dotted broken lines in the figures illustrate unclaimed features of the bag dispenser that form no part of the claimed design. The dash-dot-dash broken lines in the figures define boundary lines that form no part of the claimed design.

The logo shown in FIG. 7, and forming no part of the claimed design, is a registered trademark of Diggs Inc.
